(74) Attorney, Agent, or Firm — I. Morley Drucker;
Buchalter(57) **CLAIM**

The ornamental design for a boot upper for footwear, as shown and described.

DESCRIPTION

FIG. 1 is a front perspective view of a first embodiment a boot upper according to the present invention;

FIG. 2 is a right side elevation view of the boot upper;

FIG. 3 is a left side elevational view of the boot upper;

FIG. 4 is a front elevation view of the boot upper;

FIG. 5 is a rear elevation view of the boot upper;

FIG. 6 is a top elevation view of the boot upper;

FIG. 7 is a front perspective view of a second embodiment of the boot upper;

FIG. 8 is a right side elevation view of the boot upper;

FIG. 9 is a left side elevational view of the boot upper;

FIG. 10 is a front perspective view of a boot upper;

FIG. 11 is a rear elevation view of the boot upper; and,

FIG. 12 is a top elevation view of the boot upper.

The broken lines are solely for the purpose of illustrating unclaimed areas and form no part of the claimed design.
